UNITED STATES PATENT OFFICE

CLINTON ALVORD, OF WORCESTER, MASSACHUSETTS, ASSIGNOR TO WORCESTER LOOM WORKS, OF WORCESTER, MASSACHUSETTS

GRIPPER FOR TUFT WEAVING

Application filed October 10, 1929. Serial No. 398,644.

This invention relates to the weaving of tufted pile fabrics and has particular reference to that class of looms in which the strands of tuft yarn are grasped by grippers, 5 the proper lengths of tufts cut off, and transferred by them to the tuft forming position in the shed of the loom.

The main object of this invention is to hold a multiplicity of accurately gauged grippers 10 rigidly in place. A further object is to form a number of accurate grippers into a unit that can be attached quickly to the loom with other similar units and thus save valuable time in the starting up of a new loom.

15 Another object of this invention is the method of thus assembling a number of grippers into a unit.

A further object is to produce a short nose gripper.

20 These and other objects are shown in the drawings, described in the specification and pointed out in the claims.

Fig. 1 is a side elevation of an assembled unit of grippers.

25 Fig. 2 is a perspective view of the base of a unit.

Fig. 3 is a side elevation showing the soldering mold.

Fig. 4 shows the rivet which is cast with 30 the unit and

Fig. 5 is an enlarged drawing of the jaw rivet.

The grippers 1, having movable jaws 2 pivoted at 3, are cast in solder 4 at their butt ends 5 so that a number commonly twenty-one are held in spaced relation side by side. Base 6 is soldered to the butts 5 at the same time the several grippers are soldered together and the whole unit of grippers and 35 base is finally attached to the square slotted gripper bar 7 by the two cap screws 8.

The bar 7 has a series of transverse key ways 9 into which the keys 10, formed on each base 6, fit and the several units are registered thereby side by side along the bar. The base 6 is provided with a dove-tail 11 which fits into a reverse opening 12 in the butt of each gripper and the solder flows into the space between these matching dove-tails 40 and holds the gripper to the base. A notch

13 is formed in the butt of each gripper suitable to receive the double headed rivet 14 which is soldered therein, one head 15 appearing on one side of the soldered unit while the opposite head 16 appears on the other side thereof, the heads being larger than slot 13. The slotted gripper bar 7 is attached to suitable operating levers, not shown, in the loom and they perform their function of accurately positioning the gripper in the usual manner.

It has heretofore been customary to bolt four grippers side by side to a slotted bar by a single bolt, an individual slot for each gripper, and in all such cases the outcome 55 is that the relatively unimportant bases of contiguous grippers are accurately located at an even and parallel spacing while the very important gripping points 17 and 18 are likely to toe in or out according to small inaccuracies in the straightness of the various grippers. After the grippers are thus attached, it becomes necessary to bend the grippers that are not in perfect alignment all the way 60 from the point 17 to the part 19 for if the grippers are not substantially parallel at these and intermediate points good weaving 65 will be impossible as there will be unequal room for shedding of warps and a possible 70 non-shedding of some of the warp ends because of lack of space for the strands of warp. When four are held by one bolt as is usual practice, the area of the metals in contact is so small and the leverage so great that the grippers are apt to work loose causing inaccurate pile formation. My new method of forming a multiplicity of grippers into a rigid unit eliminates this defect.

By my new and unique method of assembling the grippers I am enabled to produce 80 units of several grippers that are spaced at a uniform distance at these necessary points. Grippers of a substantial degree of straightness are placed in the soldering mold 20 in which the comb 21 holds and guides them 85 near the points while comb 22 similarly registers them near the portion 19. The bases 6 project into the solder mold recess 23 and because there are but two guide combs 21 and 22 the grippers slip into position without 90 95 100

forcing and consequently without distortion. The double headed rivet is in position along with the base 6, a flux is applied and the solder is poured into the mould and allowed to set or harden, after which the cast unit of grippers is removed from the mold by opening it at line 25, whereupon the grippers are found to be lined up in spaced relation of a good commercial accuracy in those portions that are essential. I therefore obtain grippers that are true and accurate at the necessary points and avoid the former expensive and unsatisfactory bending. The mould which is divided at 25 is fastened together by means not shown.

In placing the various grippers in the mold the extreme points 17 bear against the bar 24 of the mold while the teeth 26 of the grippers mesh with the teeth 27 which are formed on the bar of the mold for that purpose. The individual springs 28 contact with the grippers at 29 and hold them pressed in yielding contact against the teeth of the mold and the bottom 30 of the comb 22. Thus I am assured that each gripper in every unit is lined up with its neighbors as to point 17 and teeth 26 without subsequent bending as formerly after the old fashion of assembling these important elements of a tuft weaving loom.

The slotted gripper bar 7 is grooved longitudinally to take the gripper base 6, two walls 31 and 32 on either side of the base assuring that the several units of grippers, which make up a loom width, line up with each other when fast in place on the shaft.

This may be termed a short nosed gripper, since the pivot joint 3 is placed substantially half as far from the tip of the jaw as in the ordinary gripper. This produces a stiff gripper and one in which the points of the gripper and jaw line up laterally. The tail 33 extends backward far enough to allow plenty of room for the passage of the weft needle 34 of the loom. This tail also has a fin 35 that is thinned down to match a slot milled in the guide 36 forming a part of the gripper body, and the parts are concentric with the center of rivet 3 so as to assure that the jaw will open and shut correctly. The guide 33 keeps the sides of the tail of the jaw in line with the sides of the gripper body so that the two present a flat surface for the possible lateral rubbing of the thin reed dents which pass between the grippers when they are down in the shed. Thus there is no danger of a reed dent catching on a projecting surface of a jaw tail. Also this guide assists in retaining the two jaws in lateral line with each other because it co-acts with the joint of the pivot 3 in so doing. Again this guide keeps a loose pivot joint from rocking laterally and causing an edge 37 of the jaw from sticking out beyond the line of the gripper body and presenting a projection that might contact with a moving reed dent and cause damage.

The disk 38 at the end of the tail of the jaw is acted on by a wing shaft, not shown, when opening and closing a set of grippers.

The body 1 and jaw 2 are halved in at the pivot as shown in Fig. 5. The post rivet at 3 has a countersunk head 39 already formed on it, which co-acts with the countersunk hole in the jaw, while the shank 40 is smaller and fits snugly into the hole in the body even before it is riveted up so as to bring the underneath side 41 of the rivet head down firmly on the counterbored seat 42 in the body. This leaves the jaw free to move on the rivet head while held to the gripper body.

The accuracy of the workmanship in the individual grippers and in the casting molds produce units of grippers which, when made fast to the bar 7, register by the teeth in an even straight line and in two abutting units space uniformly with those in either unit.

I thus obtain a far better job of lining up the grippers than by the old method, they are held more firmly to the gripper shaft, and it is all done in much less time, especially in the assembling of the units with the slotted bar, and I can weave a more even fabric.

Having thus clearly described my invention and illustrated it fully in the drawings, what I claim as new and desire to secure by Letters Patent is:—

1. In combination, a plurality of gripper units each composed of a multiplicity of grippers for tuft weaving that are spaced and permanently held together by solder, each unit being provided at its base with a registering spline, and a slotted gripper shaft on which said units are spaced by means of the co-acting splines and slots and to which said units are quickly attached and readily removed.

2. A new article of manufacture consisting of a plurality of grippers for tuft weaving held in spaced relation by solder at the butts thereof, and having a member embedded in the solder, and adhering thereto, said member having a relatively large head which overlaps the outer side of an outside gripper at the butt thereof to act as a mechanical and supplementary retainer for said gripper.

3. A new article of manufacture consisting of a plurality of grippers in spaced relation for tuft weaving, a base for the grippers interlocked with the butts thereof, a rivet with a head overlapping an outer gripper at the butt thereof, and solder permanently connecting the various parts together as a unit.

4. In a loom in combination, a plurality of units composed of grippers for tuft weaving held in spaced relation at their butts by solder and with a base for each unit attached to the butts of the grippers by the solder and provided with a registering spline, a carrier bar for said units having a longitudinal groove into which said bases fit snugly and provided

with lateral slots for the splines whereby said units are registered relative to each other, and means for attaching said units to said bar.

5. A unit of grippers for a tuft weaving loom composed of several individual grippers associated with a base, the ensemble being held together by solder, with the grippers spaced thereby to agree with the tuft insertion means of a loom, said ensemble being provided with registering means where-
10 by a multiplicity of said units may be operatively registered across a loom to form a desired width of accurately spaced grippers.

6. A gripper holding bar for a tuft weaving loom provided with a series of formations for registering a multiplicity of gripper units therealong, there being one formation for each unit, said formations being located to afford even spacing of an entire series of gripper units when registered thereby.
